UNITED STATES PATENT OFFICE.

DAVID BOURQUE, OF AMESBURY, MASSACHUSETTS, ASSIGNOR TO G. W. J. MURPHY COMPANY, OF AMESBURY, MASSACHUSETTS, A CORPORATION OF MASSACHUSETTS.

SOCKET FOR FASTENERS.

1,300,338.

Specification of Letters Patent. Patented Apr. 15, 1919.

Application filed May 25, 1918. Serial No. 236,502.

To all whom it may concern:

Be it known that I, DAVID BOURQUE, a citizen of the United States, and a resident of Amesbury, in the county of Essex and 5 State of Massachusetts, have invented an Improvement in Sockets for Fasteners, of which the following description, in connection with the accompanying drawings, is a specification, like characters on the drawings representing like parts.

This invention relates to stud and socket fasteners of the type used for fastening the curtains of motor cars and for similar purposes, and the object more particularly is 15 to provide an improved construction of the female member or socket.

My invention will best be understood by reference to the following description of an illustrative embodiment thereof taken in 20 connection with the accompanying drawings wherein:—

Figure 1 is a plan view of the fastener in assembled relation, looking to the left in Fig. 2;

Fig. 2 is a section on the line 2—2 of Fig. 1;

Fig. 3 is a section on the line 3—3 of Fig. 2 and provides a plan view of the socket member;

Fig. 4 is a plan of the outer element of the socket as viewed from the right in Fig. 2; and

Fig. 5 is a similar view of the inner element.

The more usual manner in which stud and socket fasteners are at present used is to provide a socket or eyelet on a curtain or other movable member and secure it to a stud projecting from the fixed member to 35 which the curtain is to be fastened, such for example as the body of a motor car. These projecting studs are not attractive in appearance and they sometimes catch the clothing of persons using the vehicle and tear the same. My invention contemplates more particularly the construction of an improved 40 form of socket which can be set flush or substantially flush with the body of the motor car and with which a stud carried by the 45 curtain can be engaged.

Referring to the drawings, I show at 7 a portion of some relatively fixed element, such for example as the body of an automobile, adapted to receive a socket, the con-

struction of which will be hereinafter more 55 fully described, and a curtain 9 to which is secured a stud 11 adapted to be engaged with said socket. For purposes of illustration I have shown the stud and socket fastener as being of the type as shown in the 60 patent to Fred S. Carr 1,038,288, Sept. 10, 1912. The particular form of fastener, however, is not material to my invention.

The socket member here shown embodies in its construction a substantially cylindrical casing which may consist of an outer cup-like member 13. Herein the wall corresponding to the bottom of the cup is presented outwardly toward the stud 11 and is perforated to receive the same, and the cylindrical wall corresponding to the sides of the cup is provided with screw threads 15 which are conveniently embossed from the metal, as here shown. The cup is adapted to receive a wire jaw 17 for engagement with the 75 stud and this may be held in place by a second cup-like member 19 having a bottom flange 21, adapted to oppose the bottom of the first cup-like member and in co-operation therewith form a chamber for receiving the 80 jaw, and having a cylindrical flange formed with screw threads 23 adapted to engage with interior screw threads on the member 13. If the threads 15 on the member 13 are embossed as described, they may be made to 85 provide both exterior threads and interior threads to receive the threads 23.

As shown in Fig. 5, the member 19 may be provided with openings 25 to receive a suitable spanner and there may be portions 90 27 struck up from the flange 21 thereof and adapted to engage the bottom wall of the outer member 13, thus to limit the telescoping movement of the two elements and determine the depth of the jaw-receiving 95 chamber formed by them. Herein certain of these elements are also adapted to serve to position the jaw 17 to insure functioning of the same as described in the Carr patent already referred to and they may fulfil similar 100 functions in connection with other forms of jaws.

The socket member consisting of the parts already described being assembled, it may be inserted in a suitable opening in the body 105 7, the screw threads 15 engaging the margin of the opening. As appears in Figs. 3 and 4, the outer cup-like member is preferably

provided with openings 29 to receive a suitable spanner so that the socket member can be conveniently screwed into the opening. The member may be thus set substantially flush with the body of the car, giving it a neat appearance and eliminating any projecting portions which might catch and tear the clothing of users.

While the exterior threads 15 on the socket might be formed in any suitable manner, I preferably emboss them from the sheet metal forming the cup 13, as already described. The threads of the inner cup-like member 19 will reinforce such embossed threads.

Having thus described one particular embodiment of my invention as applied to one known type of stud and socket fastener, what I claim as new and desire to secure by Letters Patent is:—

1. A socket for a stud and socket fastener comprising a cup-like element having a base apertured to receive a stud and an exteriorly threaded cylindrical wall, and stud-engaging means housed inwardly of said wall and presented adjacent the aperture of the base, said socket adapted to be directly screwed into a supporting member.

2. A socket for a stud and socket fastener comprising two cup-like members one being received within the other, stud-receiving jaws between said members and exterior threads on the outer member.

3. A socket for a stud and socket fastener comprising a cylindrical cup-like member having embossed threads on the cylindrical surface thereof, another member received therein and having threads fitting said em-

bossed threads on the inner side and stud-receiving jaws housed between the members.

4. A socket for a stud and socket fastener comprising a member having a front wall and a cylindrical, exteriorly threaded wall, an element received therein and having a portion presented in opposition to said front wall to provide a jaw-receiving chamber and projections on said element to engage said front wall.

5. A socket for a stud and socket fastener comprising a member having a front wall and a cylindrical, exteriorly threaded wall, an element received therein and having a portion presented in opposition to said front wall to provide a jaw-receiving chamber, projections on said element to engage said front wall and jaws in said chamber engaged and positioned by said projections.

6. In combination with a supporting member, a socket carried thereby having a front plate set substantially flush with said member and apertured to receive a stud and a threaded hollow cylinder carried by the front plate and directly screwed in said member, the interior of the cylinder providing a space wherein is housed stud-engaging means.

7. A socket for a stud and socket fastener comprising a socket having a wall apertured to receive a stud, a flange rising from the wall, a plate interiorly fitting and received by the flange and having projections contacting with the wall thereby to define a jaw-receiving chamber.

In testimony whereof, I have signed my name to this specification.

DAVID BOURQUE.
